DESIGN FOR A WINDOW-SHADE.

Design No. 13,299, dated September 19, 1882.

UNITED STATES PATENT OFFICE.

ERNEST J. HAMM, OF GREENVILLE, NEW JERSEY.

DESIGN FOR A WINDOW-SHADE.

SPECIFICATION forming part of Design No. 13,299, dated September 19, 1882.

Application filed August 16, 1882. Term of patent 3½ years.

To all whom it may concern:

Be it known that I, ERNEST J. HAMM, a citizen of the United States, residing at Greenville, in the county of Hudson and State of New Jersey, have invented and produced a new and original Design for Window-Shades, of which the following is a specification.

The drawing illustrates the design as applied to window-shades.

10 The design consists of horizontal stripes having between them a central figure, from the upper and lower part of which extend arms or branches decorated with flowers and leaves, substantially as hereinafter more fully described. Outside of the stripes may be arranged a further ornamentation of figures and leaves, substantially as hereinafter more fully set forth.

20 In the drawing, the letters A A designate horizontal stripes. Between these horizontal stripes is arranged a central figure, B. From the lower part of the central figure, B, extend arms or branches C, which arms or branches are decorated with flowers D E. From the upper part of the central figure, B, extend arms or branches F, which arms or branches are decorated with leaves G and flowers H I. Outside of the horizontal stripes A A, I may arrange ornaments K and leaves or branches L, thus giving to the design a fuller appearance.

What I claim as new, and desire to secure by Letters Patent, is—

1. The design for window-shades, substantially as herein shown and described, the same consisting of horizontal stripes A A, having 35 arranged between them a central figure, B, arms or branches C, extending from the lower part of the central figure, and being decorated with flowers D E, and arms or branches F, extending from the upper part of the central figure, 40 and being decorated with leaves G and flowers H I.

2. The design for window-shades, substantially as herein shown and described, the same consisting of horizontal stripes A A, ornaments K, and leaves L, arranged outside of the stripes A A, central figure, B, arranged between said stripes A A, arms or branches C, extending from the lower part of the central figure, and being decorated with flowers D E, 45 and arms or branches F, extending from the upper part of the central figure, and being decorated with leaves G and flowers H I.

In testimony whereof I have hereunto set my hand and seal in the presence of two subscribing witnesses.

ERNEST J. HAMM. [L. S.]
